UNITED STATES PATENT OFFICE.

GEORGE B. TAYLOR AND HENRY B. NICHOLS, OF PHILADELPHIA,
PENNSYLVANIA.

DESIGN FOR A RAILROAD-RAIL.

SPECIFICATION forming part of Design No. 28,848, dated June 14, 1898.

Application filed April 20, 1898. Serial No. 678,311. Term of patent 14 years.

To all whom it may concern:

Be it known that we, GEORGE B. TAYLOR and HENRY B. NICHOLS, citizens of the United States, residing at the city of Philadelphia, 5 in the county of Philadelphia and State of Pennsylvania, have invented and produced a new and original Design for Railroad-Rails, of which the following is a specification, reference being had to the accompanying drawings, forming part thereof, in which—

Figure 1 is a perspective view of the rail of our design, and Fig. 2 is a transverse section through the same.

The leading feature of design of our invention consists of the unitary structure made the subject of illustration, having the shape or configuration shown and hereinafter described.

Referring to the drawings, A represents the

rail, in shape or configuration as shown, with 20 the bases a and a' , and staggered depressions or recesses b and b' , and vertical recess or depression c extending into the body of the rail.

Having thus described our invention, what 25 we claim as new, and desire to secure by Letters Patent, is—

The design for a railroad-rail, substantially as illustrated and herein described.

In testimony whereof we have hereunto set 30 our signatures in the presence of two subscribing witnesses.

GEO. B. TAYLOR.
HENRY B. NICHOLS.
